UNITED STATES PATENT OFFICE.

NEWMAN H. HOLLAND, OF WEST ORANGE, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed August 14, 1924. Serial No. 731,952.

This invention relates to electromagnetic devices of the balanced armature type such as are used in sound recording and reproducing apparatus.

5 The object of the invention is to provide an electromagnetic vibratory system which is capable of efficiently and faithfully responding to vibrations of all frequencies within a wide range, such as that represented by speech or music.

10 In general, the invention provides slightly bowed spring members opposing the magnetic pull on the armature by longitudinal stresses introduced in the spring tension members which stresses vary in substantially the same manner as the magnetic pull, thereby providing a vibratory system in which the displacement of the armature is substantially proportional to the amplitude or the 15 force of the impressed vibrations.

15 In the preferred embodiment of the invention, the magnetic pull on the armature is opposed by forces applied to the vibratory system through two slightly bowed tension members disposed on opposite sides of the axis of oscillation. When the armature is in its normal position, the tension is the same in each of the members. When the armature is displaced in one direction from its normal 20 position, the tension in one of the bowed members will increase rapidly due to the tendency of the member to straighten out. When the armature is displaced in the opposite direction from its normal position the 25 tension in the other member will increase rapidly for the same reason. Since the forces are applied substantially longitudinally of the tension members, the longitudinal displacement of the ends of the members 30 attached to the vibratory system is exceedingly small compared with the transverse displacement at the knee or bend in the tension members. The deflection does not follow Hook's law; i. e., the displacement is not 35 directly proportional to the pull, as in the case of simple springs where the elasticity is constant, but is a function of elasticity and pull, both of which are variable. The tension members may be likened to a toggle- 40 joint in which the action is reversed, or to a horizontal line which has been deflected by a weight suspended intermediate the ends thereof. The longitudinal stresses in the line increase rapidly as tension is applied to

lift the weight, and the line approaches the 55 horizontal.

According to another feature of the invention, a vibratory system is supported on knife edges by a flexible rod extending through the support parallel to the knife 60 edges, and a pin through the vibratory member engages the rod, which is deflected by adjusting the pin until its point of engagement therewith is substantially in line with the 65 axis of oscillation.

70 In the drawings; Figs. 1, 2 and 3 are respectively sectional side and top views of a phonograph reproducer employing the invention; Figs. 4 and 5 are enlarged detail views of the invention; Fig. 6 is a fragmentary view showing the support for the vibratory member; Fig. 7 shows the invention applied to driving the diaphragm of a loud 75 speaker; Figs. 8 and 9 show modifications of the invention; and Fig. 10 is an end view 80 of the modification shown in Fig. 9.

85 Referring to the drawings, there is shown a permanent magnet 13 having pole pieces 11 and 12 between which are supported the usual actuating coils 14 and 15 which surround opposite ends of the armature 16 as in well known electromagnetic structures. The armature 16 is supported on a bar 20 and extends transversely thereof. A block 18 secured to the 90 magnet 13 by means of screws 19 is provided with U shaped extension arms 22, each of which terminates in a knife edge 17 which engages recesses in the bar 20. The arms 22 are provided with holes, parallel to the 95 knife edges and at a short distance therefrom, in which is inserted a light flexible rod 23. The bar 20 is provided with a hole perpendicular to the axis of oscillation in which is loosely fitted a pin 24 provided with an eye at one end through which the rod 23 passes. The opposite end of the pin 24 is threaded and provided with a nut 25 by means of which rod 23 is deflected preferably until its point of engagement with the 100 pin 24 is substantially in line with the knife edges 17. The stiffness and mass of the rod 23 do not therefore influence the vibrations of the armature 16.

105 Secured to the opposite sides of block 18 by any suitable means such as bolt 26 are springs 27 and 28 which have a slight initial bow. The holes in the springs 27 and 28

through which the bolt 26 passes may be elongated to provide for adjustment. The opposite ends of the springs are secured under the nut 25 to the bar 20. The springs 27 and 28 may be made of one piece and secured at the center to the bar 20. They are preferably made of flat spring material and given a slight bow or deflection intermediate their supported ends. The initial deflection 10 and the proportions of the springs depend upon the distance from the axis of oscillation to their point of attachment to the oscillatory member and also upon the strength of the magnetic field.

15 Since the tension in the springs 27 and 28 increases very rapidly with the displacement of the armature, close coupling may be obtained between it and the pole pieces with a resulting increase in efficiency.

20 As shown in Fig. 2 the end of the bar 20 may be provided with a stylus holder 30 for a stylus 31, as in the case of the usual phonograph reproducer or recorder, and the whole magnetic structure may be mounted on a 25 suitable swinging arm 32. In the case of the receiver shown in Fig. 7 the bar 20 may be provided with a short transverse arm 33 to which a diaphragm 34 may be connected by means of a rod 35.

30 In the modification shown in Fig. 8, the knees of the springs 27 and 28 are reversed and connected together by a light flexible member such as a wire or thread 36 to the center of which is attached one end of a helical spring 37, the opposite end of which is secured to an adjusting screw 38 extending through a hole in the block 18. A nut 39 is provided for adjusting the tension in the spring 37 which in turn exerts tension 40 in the springs 27 and 28. It will be noted that owing to the double toggle joint arrangement any slight increase in the tension in the helical spring 37 will introduce very large tensile forces in the springs 27 and 28.

45 Figs. 9 and 10 show two views of another modification in which the balancing springs 40 and 41, similar to springs 27 and 28, are attached to the end of the armature 42 of a receiver such as shown in Patent No. 50 1,365,898 of January 18, 1921, to H. C. Egerton.

55 Although the invention has been illustrated with sound recording and sound reproducing apparatus, it is obvious that it may readily be adapted to any magnetic structure employing a balanced armature.

What is claimed is:

1. In an electromagnetic device, a magnet, 60 a vibratory member comprising an armature adapted to vibrate in the field of said magnet, and means comprising a spring tensioned longitudinally adapted to flex in a plane perpendicular to the axis of oscillation of said vibratory member and to exert

a pull thereon which varies in the same manner as the magnetic pull exerted on said armature thereby balancing the armature for all positions in the magnetic field.

2. In an electromagnetic device, a magnet 70 providing a magnetic field, a vibratory member comprising an armature adapted to vibrate in said magnetic field, and a spring member longitudinally tensioned and having a slight lateral deflection therein, said member being adapted to flex in a plane perpendicular to the axis of oscillation of said member to oppose the magnetic pull on the armature by the tension exerted therein.

3. In an electromagnetic device, a magnet 80 for providing a magnetic field, an oscillatory member having an armature disposed in said field, a mounting for said oscillatory member, and a flexible member having an initial lateral deflection intermediate its ends 85 which is small as compared with its length, one end of said flexible member being fixed to said mounting and the other end attached to said oscillatory member, the longitudinal displacement of said end attached to said oscillatory member being less than the lateral displacement of the flexible member at its bend for movements of said armature.

4. In an electromagnetic device, a magnet providing a field, an armature disposed 95 therein, and longitudinally tensioned means for balancing said armature in said field, said means comprising a slightly bowed spring adapted to straighten and buckle in accordance with the oscillations of said armature.

5. In an electromagnetic device, a magnet providing a field, an armature disposed therein, and a pair of slightly bowed longitudinally tensioned springs disposed one on each side of the axis of oscillation of said armature for opposing the magnetic pull on said armature, said springs being alternately straightened and buckled in accordance with the oscillations of said armature.

6. In an electromagnetic device, a magnet providing a field, an armature adapted to oscillate therein, means for balancing said armature in said field, said means comprising slightly bowed springs on each side of the axis of oscillation, and means associated with said springs intermediate their ends for introducing longitudinal stresses therein.

7. In an electromagnetic device, a magnet providing a field, an armature disposed to oscillate therein and means for balancing said armature in said field, said means comprising slightly bowed springs, one on each side of the axis of oscillation, flexible means for tying said springs together intermediate their ends and an auxiliary spring connected to said tying means for exerting tension in said balancing springs.

8. In a vibratory system for the transmission of sound wave energy, a vibratory mem-

ber, a support therefor, means for holding said vibratory member in pivotal relation with said support, said means comprising a flexible rod and means carried by said vibratory member for flexing the center of said rod substantially to the axis of oscillation.

9. In an electromagnetic device, a magnet providing a steady field, a vibratory system adapted to vibrate in said field, slightly bowed tensional members for balancing said system in said field, a support for said vibratory system, and a transversely flexed member for securing said system in pivoted relation to said support the mid-portion of said flexed member being in line with the axis of oscillation.

10. In an electromagnetic device having a magnet and an armature adapted to vibrate in the field of said magnet, a support, a tension member between said armature and said support for compensating for the magnetic pull on said armature, said tension member being slightly bowed from a perpendicular to the plane of said armature and its axis, the depth of the bow being slight compared with the length of said tensioned member.

11. In an electromagnetic device having a magnetic and an armature adapted to vibrate in the field of said magnet, a support, a tension member between said support and

said armature on each side of the axis thereof, said tension members being slightly bowed from a perpendicular to the plane of the armature and its axis, the tension in one of said members increasing rapidly with the displacement of said armature and substantially in accordance with the law of the magnetic pull.

12. In an electromagnetic device, an oscillatory member, a light resilient member having one end attached to said oscillatory member and extending substantially normal to a radius through its point of contact with said oscillatory member and the axis of oscillation, said resilient member having a slight lateral displacement whereby a slight displacement of the armature causes a longitudinal pull in said member for controlling the vibrations of the armature, the displacement of said oscillatory member from its normal position at the point of attachment of said resilient member thereto being less than the lateral displacement of said resilient member for movements of said armature.

In witness whereof, I hereunto subscribe my name this 11th day of August, A. D., 1924.

NEWMAN H. HOLLAND.
